Attorney

UNITED STATES PATENT OFFICE.

JOSEPH DE JOHN, OF DETROIT, MICHIGAN.

VEHICLE DOOR LOCK.

Application filed March 12, 1924. Serial No. 698,770.

To all whom it may concern:

Be it known that I, JOSEPH DE JOHN, a subject of the King of Great Britain, residing at Detroit, county of Wayne, State of Michigan, have invented a certain new and useful Improvement in Vehicle Door Locks, and declare the following to be a full, clear, and exact description of the same, such as will enable others skilled in the art to which it pertains to make and use the same, reference being had to the accompanying drawings, which form a part of this specification.

This invention relates to vehicle door locks, and has for its object an improved construction, by means of which, in a four-door sedan for instance, but two locks are necessary, one on each side of the vehicle, each one like the other, and each lock being located in the pillar or upright between the adjacent free swinging edges of the doors, the selective opening of one or the other of which is regulated by the direction in which the handle is turned, either from the inside or from the outside. My invention not only makes possible the reduction of the necessary number of locks from four to two and their all being of one sort, but as well avoids the necessity of there being a lock with its appurtenant projecting handles on the edge of the door, upon which one's clothing otherwise easily catches when entering or leaving the vehicle.

In the drawings:

Figure 1 is an elevational view of one of my locks installed in the pillar of the vehicle body, and flanked by the free swinging edges of a pair of doors.

Figure 2 is a plan view taken along the line 2—2 of Figure 1.

Figure 3 is an elevational view of the lock, with the contained operative parts dotted in in their proper relative positions.

Figure 4 is a perspective of a preferred form of latch.

Figure 5 is a partly sectional elevational view similar to that of Figure 3, but showing the operative parts contained within the housing in full lines.

Figure 6 is a view similar to Figure 5, but showing the locking element inactive, and with the possible swing of the locking lever indicated in dotted line positions.

Figure 7 is a sectional side elevational view taken along the line 7—7 of Figure 1.

A indicates the pillar of the vehicle top,

flanked by the doors B and C. Fitted in a suitably cut away portion of the pillar is the lock E, whose shell may, if desired, be provided with projections D, for insuring the accurate and firm installation of the housing in the wood of the pillar. The doors B and C are provided with the latch recesses F, such as are usually found in the door frame, whereas the latches G and H are limitedly slideable in a horizontal plane in the housing E. Each of these latches, as brought out particularly in Figures 4, 5 and 6, has an inwardly extending branch, as g and h, at the end of which are upstanding knobs g² and h², and as brought out in Figures 5 and 6 particularly, these projections of the respective latches lie one above another, each entire latch being yieldingly projected outward by the respective springs g³ and h³. Through and over the intermediate or cut-away portions of the latch projections extends the depending lever L, which is mounted on a squared portion of the shaft K, whose outer end carries the outside handle J, and whose inner end carries the inner handle M; the cut-away portion of each interior projection is of sufficient length so that when the shaft K is turned, and with it the lever L is rocked, the latch-engaging portion of the lever can, as brought out in Figure 6, rock limitedly in either direction, without encountering the outer bulkier portion of the latch, though as to the cut-away and projecting portion respectively of the other latch piece, the swing of the lever L serves to retract it against the pressure of its spring g³ or h³; thus, if the outside handle is turned to the right, the latch H, which controls the opening of the door C, is retracted. If the outside handle J is swung to the left, the latch G, which controls the possible opening of the door B, is retracted. If the inside handle is actuated in the same direction as regards the outer, just the reverse of these opening operations would take place.

In order to provide for locking of the interior of the vehicle against access from the outside, I make the lever L of such length that it reaches below the latch pieces and the lowermost one of the fixed latch guides N, so that its lower tip can engage in the suitably recessed portion P of the pivoted dog Q, another portion of whose freely swinging periphery is provided with a deep indentation R, which engages in the eccentric

and partially peripheral slot T, in the rotatable drum S, which may be controllably actuated to either locking or unlocking position of the dog with respect to the lever L, 5 by means of a key inserted in the combination or tumbler lock V, thus locking both doors at once. In the case of the doors on the "off" or left hand side of the vehicle, in place of the removable key-controlled lock, 10 there may be provided a non-removable key, actuated from the inside to locking position by turning through a quarter turn, in a manner now used on some vehicles.

In order to accelerate the prompt outward swing of either door when its latch is retracted, there may be provided springs of some appropriate type, such as are shown at W in Figures 1 and 2, which act at a slight angle against the striker plates of the locks, 20 and against which said striker plates wipingly and compressingly engage when the doors are again swung to closed position.

What I claim is:

1. A door lock, having, in combination 25 with a pair of horizontally disposed latch members each capable of independent movement to and fro, a manually rockable shaft provided with a depending portion adapted to retractingly engage either of said latch members, independent spring members appurtenant to each of said latch members whereby their retractile movement is yieldingly opposed, and a cam-actuated locking dog adapted to engage the depending portion of said rockable shaft when the same 30 is in neutral position as regards said latch members.

2. In a plural door lock, in combination

40 with a containing shell, a pair of limitedly 45 slideable latch members projecting from either side thereof in positions of substantial alignment with one another, means for yieldingly holding each latch member in projected position independently of the other, a rockable shaft engaging through said shell transversely of the path of possible movement of said latch members, means carried by said shaft for operatively engaging either one of said latch members to effect its retraction against the pressure of its spring while leaving the other latch member unactuated, and externally actuatable means for locking said last-mentioned means in neutral position.

3. In a door catch, the combination, with 50 a housing, of a rockable shaft engaging therethrough, a projecting lever carried by said rockable shaft, a locking dog normally 55 out of engaging position with respect to said lever, a key-actuatable cam whereby said locking dog may be raised to locking position with respect to said lever when the latter is in neutral position, a pair of limitedly 60 slideable latch members positioned in substantial alignment in the sides of the housing and adapted to be retracted by the swing 65 of said lever against one or the other, and separate spring members for yieldingly holding said latch members in projected position.

In testimony whereof I sign this specification in the presence of two witnesses.

JOSEPH DE JOHN.

Witnesses:

E. A. DE JOHN,
WILLIAM M. SWAN.
